SIGNATURE GATHERING MACHINES

William Q. Pendley, 38 Hazelrig Drive SE, Atlanta, Ga.
Filed Nov. 29, 1956, Ser. No. 625,140
15 Claims. (Cl. 270—58)

This invention relates to a signature gathering machine and particularly to a machine of this sort for use in the book printing and publishing field or in any applications where it is desirable to accumulate a group of individual sheets or signatures into a properly stacked sequence, as when gathering a number of sheets of a book into the composite group of sheets in sequence.

There are machines in the prior art which sort sheets of paper or the like into a composite group but these machines are quite complex and the better known operate on a lineal arrangement of pulling the sheets from a moving line. Such machines are very expensive and are beyond the reach of the ordinary catalogue bindery or small book publisher. A definite demand has existed for time for a signature gathering machine of more simple arrangement and which can be adapted to handle small numbers of signatures in a small floor space rather than being practical in use only in a large floor space as in the case of the larger machines. The present invention presents such a machine. A machine of the instant invention with an 8 foot diameter can handle 16 stations.

Generally described, without regards to scope of patent coverage and therefore without this being a restriction thereon, the machine is organized and arranged for operation in a circular motion using a basic circular table on which is located any number of individual signature stations near the outer periphery of the table in sequence arcuately spaced from each other. The table is rotatably supported about a column which is mounted and supported on a sub-frame assembly beneath the table and the sub-frame has wheels thereon which support the table in its rotary movement. A power friction drive on the sub-frame drives the table slowly in rotation. Corresponding to each station on the table is a station signature lift device comprising one or more conventional vacuum cups positioned for operation against a sheet stock of signatures at the station and each vacuum cup is connected by a line to a central valve device located with one part on the table and the other part on the center column. The valve device is adapted in pre-determined timed relation to deliver suction the proper lift device at the time it is to engage and lift the top sheet of the stack. Also in conjunction with the valve device is a blower line which delivers air to a selective individual nozzle located adjacent each stack for the purpose of separating the top sheet as it is lifted. The suction lift devices are mounted above the table for vertical movement thereon and each one thereof has an individual wheel resting on an inner track above the table which track controls and determines the movement of the lift devices against the stack of signatures. According to this arrangement the track times the lift devices and the valve and track are timed together so that as the table rotates, the lift devices descend at the proper movement onto a stack and engage by suction the top sheet thereon, thereafter being moved on around to the proper place where the valve breaks the suction and releases the sheet to a stack in sequence. A ribbon conveyor removes the sheets and a stacking device synchronized with the table removes and locates the stacked sheets. Various valuable and excellently operating sub-combination elements of the invention are described herein, such as the valve arrangement for delivering the suction and the stack conveyor device for removing the stacks of sheets.

A primary object of this invention is to present a sig-

2

nature or sheet gathering machine which operates in an arcuate path in a limited space.

A further object of the invention is to provide a signature or sheet gathering machine which engages sheets in succession to lift and distribute them in proper sequence to a stacked condition.

Another object of this invention is to provide a sheet or signature gathering machine with provision for preventing an incomplete stack from occurring where one or more of the sheets were missed in sequence. In this machine, once the sorting of the sheets starts the proper sequence must remain accurate every time or the machine automatically creases further gathering.

Still another important feature of this invention is found in the arrangement whereby all the individual stacks of identical sheets or signatures remain still on the base member and the base member is moved arcuately for the picking up and the delivery of the sheets or signatures to the stacks of mixed sheets.

Additional advantages are found in the stacking arrangement operating in conjunction with the picking up of mixed sheets and in the valve arrangement for timing the suction and in other elements of the present invention or sub-combinations thereof.

Other and further objects and advantages of my invention will become apparent from the following description taken in conjunction with the accompanying drawings, wherein:

FIG. 1 is an isometric view of the machine of the present invention with the stack removal device broken away.

FIG. 2 is a partial, vertical central cross-sectional view of the machine in FIG. 1.

FIG. 3 is a top plan view of the machine shown in FIG. 1.

FIG. 4 is a bottom plan view of the valve bottom detail mounted on the column of the machine.

FIG. 5 is a top plan view of the valve detail shown from underneath in FIG. 4.

FIG. 6 is a top plan view similar to the one shown in FIG. 3 but with all the top structure broken away to expose the sub-frame assembly.

FIG. 7 is a bottom plan view of the valve top detail.

FIG. 8 is an isometric view of the detail shown in FIG. 7.

FIG. 9 is an enlarged front elevation view of the suction cup lift device with parts broken away.

FIG. 10 is a side elevation view of the device shown in FIG. 9.

FIG. 11 is an enlarged side elevation view of the signature blower nozzle.

FIG. 12 is a side elevation view of a portion of the central column with the suction and blower lines thereon.

FIG. 13 is a side elevation view of the stacking and transfer apparatus forming a part of said machine.

FIG. 14 is a top plan view of the apparatus shown in FIG. 13.

FIG. 15 is a front end elevation view of the apparatus shown in FIGS. 13 and 14.

FIG. 16 is a diagrammatic view of mechanical and electrical controls for the apparatus in FIGS. 13, 14 and 15 and showing its control and actuation from the main machine table.

The machine shown in the present disclosure has been simplified for purpose of illustration by presenting less stations than would likely be found in the commercial form of the machine. As will hereinafter appear the number of these stations may be varied depending on the use to which the machine is applied and the addition of stations is a simple matter of interposing them between those already there and adding the tubing and connections for them. It will readily appear to one skilled

in this art that the construction and operation of the machine shown is the same for the four stations shown as it would be for 10 or more stations.

Referring to the drawings, a circular base table support and conveyor member 20 is supported on and for rotation over a frame assembly 22 and about a central column member 24. Frame assembly 22 is composed of rigidly joined frame members comprising horizontal members 26, vertical members 28, and diagonal strut members 30 welded or otherwise fixedly joined. The base table member 20 is supported on the frame assembly 22 by means of caster-type wheels 32 mounted in several spaced positions on top of the frame assembly 22. Base 20 rests on and is supported by these caster wheels 32 and will rotate freely thereon about the center column 24.

Spaced about the periphery of the table 20 on the flat top 34 thereof are a number of signature or sheet stations 36 defined and located by front abutment posts 37 and a backup plate 38 forming a substantially quadrilateral space into which may be stacked a vertical stack of signature sheets 40. There are four such stations 36 shown in the present embodiment spaced around the entire periphery of the circular table 20 but as will be apparent as many stations as desired may be used. Behind each of the backup plates 38 is a pair of support lift rod members 42, 44 fixed vertically in the face of the flat top 34 and resting on and fixed to said four sets of lift rod members is an upper annular member 46 which connects all of the lift rod members together above the top 34. Mounted on each of the pair of support lift rods 42, 44 is a respective sheet lift device 48 comprising a pair of sleeves 50, 52 slidably mounted on a respective rod 42, 44 and joined by upper transverse member 54 and lower transverse member 56 to form a slidable tubular, box-like unit (see FIGS. 9 and 10). Protruding from lower member 56 outwardly substantially horizontally is a cup support and conduit member 58 having an inner tubular guide sleeve 60 and an outward tubular guide sleeve 62. Mounted for vertical movement in sleeve 62 is a smaller conduit and vacuum cup support 64 with a vacuum cup 66 operably connected thereon and a similar cup support 68 on sleeve 60 has a vacuum cup 70 thereon. A flexible line 71 connects conduit cup support 64 with conduit 58 and a similar line 73 connects cup support member 68 with conduit 58. In this respect, each station 36 is identical with the same flexible lines 71, 73 connecting the respective cups 66, 70 to the station conduit member 58. Another flexible line 72 connects on the inward end of conduit member 58 and connects it with a rigid conduit member 74 mounted on the top 34; conduit member 74, with a cut-off valve 76 having closing handle 78 and opening projection 80, leads to and connects on a central valve timing and transfer device 82 which will be described in detail.

Column member 24 is a hollow member resting on a column ground support block 84 under the machine and column has a large column lower portion 86 and a smaller upper portion 88. A blower device 90 powered by a motor 92 has a large blower tube 94 extending therefrom into the column 24 and upwardly therethrough to project from the top portion of the column 24 joining a connection member 96 on which is fixed a flexible blower hose 98 leading to and connected on the valve device 82. Likewise extending into the column 24 from the suction side 100 of an air compressor 102 powered by an electric motor 104 is a suction line or vacuum tube 106 leading upwardly through the column 24 and extending outwardly therefrom at the top thereof. A flexible suction line 108 connects on the line 106 and leads to and connects on the valve timing device 82. A second blower, flexible line 110 leads from the member 96 down to a second connection on the valve device 82.

Mounted on struts 112 fixed to the column 24 is a timing, lifting and lowering guide control track 114 of arcuate formation within the upper annular member 46.

Track 114 has a level portion and position 116 and a drop and rise portion and position 118. Extending inwardly from each upper transverse member 54 of each lift device 48 is a wheel support member 120 projecting above the track 114 and having a "skate-like" wheel 122 mounted for rotation thereon for rolling engagement on the track top. With this arrangement, each lift device 48 will move upwardly and downwardly on the rods 42, 44 according to the movement of its respective wheel 122 on the track 114. As the lift device moves downwardly the vacuum cups 66, 70 descend to the station therebelow to rest in downward position upon the top of a stack of signature sheets 40 stacked at each station 36. At this point where the cups 66, 70 rest on and against a sheet 40, the valve device 82 (as will hereinafter be described in detail) operation is such that a strong vacuum is then applied to the cups 66, 70 thereby picking up the sheet 40 on which they rest. As the sheets 40 move upwardly again along with the wheel 122 travelling upwardly on the track 114 and when the table 20 reaches the proper point, the sheets are accumulated by being dropped onto a conveyor removal apparatus 126 having moving belts 127 powered by a motor 129 and drive belt 125 which project outwardly from the above the table top 34. Sheets 124 are released to the conveyor apparatus 126 by means of suction being broken or terminated at the right time over the belts 128 according to the operation of the valve device 82. The conveyor removal apparatus 126 will be described further in connection with FIGS. 13, 14, and 15.

Valve Transfer Timing Device (82)

The valve device 82 consists of a bottom, fixed plate 128 of generally rectangular form with a central opening 130 through which the column 24 passes as the plate 128 moves therearound.

Plate 128 is mounted on the table top 34 on top of a number of connection nipples 132 leading to a flexible blower line 134 connected to a blower nozzle 135 for each station 36 and other nipples 136 leading to the conduit 74 of the vacuum lines. Both nipples 132 and 136 are welded or otherwise fixed to the bottom of plate 128 communicating with respective holes 138, 140 in the plate 128 open on the top thereof. There is, therefore, a group of outer holes 138 in communication with the blower lines 134 and inner holes 140 in communication with both the vacuum cups 66, 70. A top valve timing cover 142 has rigidly connected thereto a suction or vacuum nipple 144 in communication with a vacuum opening 146 in and through cover 142 leading into a recessed arcuate groove or transfer chamber 148; and having the main incoming vacuum line 108 connected thereto. Cover 142 also has an air pressure or blower nipple 150 attached thereto in spaced arcuate relation to nipple 144 and in communication with a blower opening 152 leading into a blower chamber or groove 154 following directly behind and in alignment with groove 148. Grooves 148 and 154 are above and in alignment with the inner holes 140 on plate 82 so that as the plate 82 revolves it passes in succession beneath the grooves 148 and 154. Another blower nipple 156 is attached to the cover 142 outwardly of nipple 144 and in communication through hole 157 in cover 142 with a recessed chamber or groove 158 which is in alignment with outer holes 138. Main blower line 98 leads onto nipple 156 and the secondary blower line 110 leads from the connection member 96 to the secondary blower nipple 150.

Valve cover 142 is adjustably held in place around column 24 by means of a split clamp collar member 160 held in place by bolts 162. Therefore, its position with respect to column 24 and the track 114 may be adjusted to vary the timing therebetween to give as accurate a relationship as desired. Cover 142 is to slidably engage the top of plate 82 and is mounted on the column so as to touch the top of plate 82 with a close fit. A light coat of oil is placed on top of plate 82 to facilitate the movement of cover 142 slidably thereover.

With the foregoing arrangement, a tight communication is formed between the suction line 168, holes 146, chamber 148 and the suction holes 140 through the bottom nipples 136, through the suction lines 74, 72 for each station 36 to each of the suction cups 66, 70. When suction is temporarily on a particular station 36 the cups 66, 70 at that station will pick up a sheet 40 and retain same until suction is broken. Likewise, following suction through line 108 is the small blower formed by vacuum line 150 through hole 152, chamber 154, the same hole 140, through lines 74, 72 to the same cups 66, 70. When the small blower communicates with the suction cups, any sheet 40 still stuck thereon is immediately blown therefrom. This serves as a positive release for disengaging sheets for release. The large blower line 98 leads through the nipple 156 through hole 157 and chamber 158 with a tight transfer of air to the large holes 138 in succession on the plate 128, through the bottom nipples 132, through the lines 134 to a respective blower nozzle 135 positioned at the side of each stack of sheets 40. As is seen in FIG. 11, the blower nozzle 135 is a closed, cylindrical member with a side slot 163 through which air is emitted under pressure against the side of the stacked sheets 40 thereby "ruffling" the sheets apart so that the lifting of the uppermost sheet is accomplished without sticking.

The operation of the valve device 82 is timed with the slant and raised positions 116, 118 of the track 114 so that suction is applied to the right station 36 just as the cups 66, 70 are dropped onto a sheet 40 to engage and stick to same. Likewise, the timing and positioning of valve cover 142 is such that the station 36 with the sheet stuck thereon releases the sheet by broken suction just as the sheet is over the belt 127 and at that time the air blast through the small air line 150 and chamber 154 connects with the suction cups 66, 70 to blast the sheet 40 therefrom.

As a unique safety factor, chamber 148 is made by its arcuate length to cover and communicate with more than one hole 140 at the same time, thereby making it necessary that the first, or lead, hole 140 have suction thereon (by having a sheet 40 stuck thereto) or else the next hole 140, and the station 36 in connection therewith cannot pick-up the sheet on which it rests and engages because suction is also lost on that hole. By this arrangement, if the first lead station 136 from hole 140 fails to make proper engagement with a sheet stack (due to a wet sheet or stuck sheet or the like) the next station 36 through hole 140 which is also in communication with valve chamber 148 cannot pick-up any sheets and then the next hole has no suction and so on until the condition is corrected. This prevents the making of an incomplete book caused by one station 36 failing to pick-up. Therefore, if any one station 36 fails to pick-up, every station thereafter will also fail. To place the machine back in operation after this has happened, several successive lines 72, 74 each has the valve 76 thereon with a long handle 78 and opening projection 80. A solenoid actuated plunger 164 is operated by a manual switch 165 to drop down into the path of the handles 78 and to strike and close same as the entire table 20 moves around. Solenoid plunger 164 is then released by hand release of the switch 165 and the projections 80, which now have been rotated into the path of a rigid rod 166 fastened by bracket 168 on the frame 46, are struck by the rod 166 as the table 20 continues to rotate thereby rotating the handles 78 and returning the valves 76 in succession to normal open position, starting when the first book station is picking up. By this arrangement, suction is again restored in the chamber 148 because one hole 140 below is closed off by valve 76 being closed while the other hole 140 therebelow is opened and then the next hole therein is opened and so on.

Table 20 is driven constantly on frame assembly 22 and wheels 32 by means of a friction drive 170 consisting of an independent drive electric motor 172 with switch 173

10

(see FIG. 6) under the table 20 driving a shaft 174 mounted on frame 22 by a belt 176. Shaft 174 has a rotatable friction wheel 178 thereon with cylindrical friction surface which engages the bottom surface of the table 20 and drives it around column 24 at a more or less constant speed. In the event anything jams the table 20 from movement, friction drive wheel 178 merely spins thereon without damage. Motor 172 is on a direct circuit with the line current and has no particular control circuit other than the simple line switch 173.

Stack Transfer

In FIGS. 13 through 16, is shown the stack transfer device 200, part of the accumulator apparatus which receives the sheets in succession from belt 127 on conveyor 126 and accumulates them into a complete book 202, and then transfers the complete book away to receive another one. This transfer device 200 is positioned immediately in front of the lower end of conveyor 126 and consists of a frame assembly 204 with horizontal members 206, vertical members 208, transverse members 210, and inclined upper frame members 211, rigidly connected together to form a box like open frame having a front transverse drive shaft 212 thereon with opposed drive sprockets 214, 216 and a rear driven shaft 218 with sprockets 220, 222 thereon. A chain 223 connects sprockets 214 and 220 and a similar chain 225 connects sprockets 216 and 222. Mounted outside of frame member 211 on one end of shaft 212 is a driven gear 224 and mounted on a stub shaft 226 in a bearing 228 on side frame member 206 is a driving gear 230 in driving engagement with driven gear 224. Splined on shaft 226 with gear 230 is a circular ratchet gear 232 and mounted in movable engagement with shaft 226 is a long crank arm member 234 having a pawl 236 thereon pivoted on a pin 235 on crank 234. Pawl 236 engages the teeth in ratchet gear 232 and will rotate the gear 232 as the crank 234 moves upwardly.

Crank 234 is confined for movement in a bracket 237 comprising a plate 238 mounted by screws 239 on inclined frame member 211 and a guide member 242 fixed thereon in spaced relation about said crank arm 234. Mounted at the top of plate 238 is an air release valve 244 actuatable when struck by the crank 234 and connected by air line 246 with a hydraulic air cylinder 248 mounted by pivot pin 250 on frame 206. Cylinder 248 has a piston rod 252 which is connected by pin 254 with crank arm 234 and cylinder 248 moves against a spring 256. Cylinder 248 receives selectively a burst of air from an air line 258 connected with an electric solenoid air valve 260 receiving a supply of air under pressure from an air line 262 supplied by any conventional air compressor 263. The electric air valve control 260, which is well known, is actuated by a solenoid therein connected by wires 264 to a micro-switch 266 mounted on frame 22 and contactable by a switch spring arm 268 mounted underneath the bottom of table top 34.

Referring to the diagrammatic operation FIG. 16, it is seen that when the switch 266 is contacted by the arm 268, as the table reaches a predetermined position at the end of one book making cycle, the switch 266 is actuated to temporarily operate the solenoid air valve 260 thereby supplying a burst of air into the cylinder 248 which drives the air piston rod 252 upwardly toward the top of the machine to the dotted lines in FIG. 13. The movement of piston rod 252 moves the crank arm 234 a limited amount sufficient to engage pawl 226 with a tooth on ratchet gear 232 and to rotate the gear 232 one tooth's distance, thereby driving gear 228 which in turn drives gear 224 which in turn moves shaft 212 to drive sprockets 214, 216 which drive chains 223, 225 and sprocket 220 and a corresponding sprocket for chain 225 on the other side (not shown).

Chains 223, 225 have upstanding fingers 270 mounted transversely spaced thereon and longitudinally spaced

along the chains to form hook positions 272 in which one complete book is stacked. The chains 223, 225 and the gears 230, 232, 224 are calibrated and timed with the switch 266 to advance one book 202 on the chains 223, 225 upon reaching the last signature station 36 on the table 34 by each cycle of the arm 234. Therefore the table 34 starts and picks up from the first signature station through the last station whereupon the stack transfer moves one book position upon receiving the last sheet.

After crank arm 234 moves the distance of one ratchet tooth of ratchet 232 it strikes the valve 244 thereby releasing the air in piston cylinder 248 which permits, by gravity and the spring 256, the piston 252 to return to down position.

The top of the stack device 200 has a cover board 272 thereon with upper surface 274 having slots 275 to accommodate the fingers 270 and the receiving end of the machine has a feed board 276 with small rubber tired pressure wheels 278 on brackets 280 held by a pair of rods 282. The signature sheets being fed in alignment from conveyor 126 are fed through the space beneath wheels 278 and dropped on the cover board 272 in a stack until a complete book stack has been made at which time the switch 266 actuates the piston 252 to move the fingers 270 against the stack thereby moving the stacks up the inclined device to be removed by hand from the upper end beneath the feed board 276. At this time the next successive space between the fingers 270 starts receiving the next stack and so on in succession as long as the machine is delivering the signature sheets 40. After chains 223, 225 have moved one interval of ratchet 232, they continue on around in such successive motions beneath the feedboard 276 with the fingers 270 and travel back to bottom position in a continuous fashion around to the top to receive more stacks. In this manner, the operation is continuous in response to the ratchet 232 and pawl 226. The movement is instantaneous and the next successive stack starts immediately. If desired, two stacking machines may be employed in "gang."

In the diagrammatic control system of FIG. 16, it is seen that a momentary closing of switch 266 by spring arm 268 (immediately upon releasing the last signature sheet in a book) energizes the solenoid control valve 260 permitting air from compressor apparatus 263 to enter cylinder 248 thereby driving arm 234 which drives gear 228 until arm 234 strikes release valve 244 thereby returning piston 252 to normal position.

Overall Machine Operation

The machine operation, which is covered in detail in the foregoing discussion, is summed up by the following: to place the machine ready for operation, each station 36 is loaded with a vertical stack of signature sheets 40 and the sheets are arranged counter-clockwise in succession in sequence according to the desired sequence for the ultimate book stack. Station No. 1 would be arranged to pick up at the proper position on track 114 and to drop first over conveyor 126, according to the position of portion 118 of track 114 and the location of switch 266, simply by placing the stacks initially in the proper order.

Line switch 173 is closed to start motor 172 thereby driving table 20 constantly and continuously. Immediately thereafter station No. 1 lowers on track 114 to engage the top sheet in its stack 40 therebeneath and at that time valve device 82 delivers suction to the cups 66, 70, lifting against the top sheet and holding same until station No. 1 rises again on track 114 to a position over conveyor 126 at which time valve 82 drops suction on cups 66, 70 and delivers a short burst of air through the cups 66, 70 blowing the sheet onto the conveyor where it is delivered to the feedboard 276 and into a stack 40 at position 272 and so on with continuous successive sheets and stations behind No. 1 until a complete book is made at the stacking device 200, at which time switch 266 is actuated at table top 34 to operate stacking device 200 to move to another book stack position and so on in succession as long as

the machine is operated and as long as there are sheets 40 for making book stacks. As stated above in detail, if at any time any station fails to pick up its sheet 40 valve 82 responds to this condition by not picking up at every following station until the condition is corrected through the valves 76. Therefore, it is virtually impossible to make an incomplete book as long as the machine is initially set-up properly.

While I have gone into great detail in describing the machine shown in the drawings with much particularity, this specification and drawing of details is not to be construed as any sort of limitation on the scope of coverage of invention since many and various alterations, substitutions, eliminations, modifications, changes, reversals, and other additions or designs may be made in the embodiment shown and described without departing from the scope of my invention as defined in the appended claims.

I claim:

1. Apparatus for gathering signature sheets and the like from a plurality of individual stacks into identical groups of mixed sheets stacked in sequence, as when gathering the individual pages of a book into the complete book, comprising, a base, an endless sheet conveyor means travelling in a pre-determined arcuate path on said base so as to be returned on each complete cycle of movement to its beginning point and having a plurality of individual sheet stations with said sheet stacks spaced in sequence thereon thereby providing individual sheet stacks travelling in a fixed position with said endless means, a sheet transfer means movable adjacent each sheet station and stack for engaging and moving a sheet from its respective stack during continuous movement of said endless member, there being one of said transfer means for each of said sheet stations, a vacuum sheet engaging member on each of said transfer means for engaging a respective sheet and for temporarily holding same as sheets are moved respectively in sequence, first control means associated with said endless means and each of said transfer means for controlling the sequence of movement thereof thereby controlling said means to move said sheets in proper sequence, a vacuum line for each of said vacuum members, a main vacuum line, a central vacuum valve transfer and timing means operating between said main line and said other vacuum lines and comprising a central valve inlet receiving said main vacuum line in closed communication therewith, a connecting chamber between and in closed communication with said central valve inlet and selectively timed in communication with at least one of a plurality of the inlets for said vacuum lines for said vacuum members at such time as vacuum is delivered to that particular vacuum sheet engaging chamber and said inlets for said vacuum lines for said vacuum members, whereby at least one of said vacuum lines is selected for suction according to the relative position of said chamber and said inlets, and whereby those vacuum lines for those vacuum members not receiving suction are not in communication with said central inlet, and means for receiving and accumulating said mixed group of sheets in sequence, said first control means and said central vacuum valve transfer and timing means being timed in synchronization to engage sheets in sequence and to hold and transfer same, in response to the timed vacuum from said central vacuum valve transfer and timing means.

2. Apparatus for gathering signature sheets and the like from a plurality of individual stacks into identical groups of mixed sheets stacked in proper sequence, as when gathering the individual pages of a book into the complete book, comprising, a base, an endless sheet conveyor means travelling in a pre-determined arcuate path on said base so as to be returned on each complete cycle of movement to its beginning point and having a plurality of individual sheet stations with said sheet stacks spaced in sequence thereon, thereby providing individual sheet stacks travelling in a fixed position with said endless means, a sheet transfer means movable adjacent each sheet station and

stack for engaging and moving a sheet from its respective stack during continuous movement of said endless member, there being one of said transfer means for each of said sheet stations, a vacuum sheet engaging member on each of said transfer means for engaging a respective sheet and for temporarily holding same as sheets are moved respectively in sequence, an actuating member on each of said transfer means, a control guide means for said actuating members to control the movement thereof, said control guide means being positioned with respect to said endless member so as to guide said actuating members for operation to move said sheet transfer means into position for said vacuum member to engage said sheet, a vacuum line for each of said vacuum members, a main vacuum line, a central vacuum valve transfer means mounted for operation between said main line and said other vacuum lines to time and control the vacuum delivered to any given sheet engaging member on a respective transfer means and comprising a central valve inlet receiving said main vacuum line in closed communication therewith, a connecting chamber between and in closed communication with said central valve inlet and selectively timed in communication with at least one of a plurality of the inlets for said vacuum lines for said vacuum members at such time as vacuum is delivered to that particular vacuum sheet engaging member, there being relative motion between said connecting chamber and said inlets for said vacuum lines for said vacuum members, whereby at least one of said vacuum lines is selected for suction according to the relative position of said chamber and said inlets and whereby those vacuum members not receiving suction are not in communication with said central inlet, said control guide means and said valve transfer means being synchronized with each other and timed with the position of said endless member to engage sheets in proper sequence and to hold and transfer same, and a sheet receiving and accumulating means associated with said endless member to receive sheets in sequence into a mixed stack.

3. The device of claim 2 wherein said control guide means is a member located continuous adjacent portions of the path of travel of said endless means and having actuating positions thereon, and said actuating members are actuated upon coming into engagement with said actuating positions on said member.

4. Apparatus for gathering signature sheets and the like from a plurality of individual stacks into identical groups of mixed sheets stacked in proper sequence, as when gathering the individual pages of a book into the complete pages of the book in sequence, comprising: a base frame, an endless conveyor means travelling in a pre-determined arcuate path in a closed arc on said base so as to be returned on each complete arc of travel cycle to its beginning point and having a plurality of individual sheet stations accommodating sheet stacks travelling in a fixed position thereon, said sheet stacks being arranged in stacks of substantially vertically disposed sheets with individual stacks spaced in sequence of desired succession along the arc of said endless conveyor, a sheet transfer device mounted for operation adjacent each of said sheet stations and including vacuum suction means to engage and lift a sheet, a track timing member mounted on said frame and extending coextensively with said endless means for at least a portion of the arc thereof and having portions thereof out of alignment with other portions thereby causing said track to run in other than a single plane, a control support member on each of said transfer devices adapted to move said transfer device in response to movements imparted thereto, said control support having a portion thereof contacting and following said track thereby being in response to the changes in direction thereof whereby said control support is moved by said change of track, a main vacuum line for all of said vacuum lines, a valve control device having a valve timing cover mounted on said frame in communication with said main vacuum line and a timing plate mounted with said endless member in communicable vacuum relation with said cover when said endless means is moving, said timing plate receiving all of the vacuum lines for said respective transfer devices and moving to receive selectively vacuum from said main line and to transfer said vacuum without loss selectively to one of said vacuum devices, said valve control device and said transfer members being timed and synchronized with each other and said endless means to deliver suction to said respective vacuum devices when said cups engage a sheet to move same and to terminate suction when said sheet has reached delivery position of release, and means for accumulating said sequence of delivered sheets in a mixed stack.

5 gaging and lifting a sheet when suction is delivered thereto, an inlet for each of said vacuum members, a central vacuum timing means mounted with said endless member in association with said sheet moving control when said 10 endless means is moving and comprising a central valve inlet receiving said main vacuum line in closed communication therewith, a connecting chamber between and in closed communication with said central valve inlet and selectively timed in communication with at least one of a plurality of the inlets for said vacuum lines for said vacuum members, whereby at least one of said vacuum lines is selected for 15 suction according to the relative position of said chamber and said inlets, and whereby those vacuum members not receiving suction are not in communication with said central inlet, said timing means actuating said sheet moving 20 control device, said control device and said transfer members being timed and synchronized with each other and said endless means to engage a sheet to move same and to terminate when said sheet has reached delivery position of release, and means for accumulating said sequence of 25 delivered sheets in a mixed stack.

5. Apparatus for gathering signature sheets and the like from a plurality of individual stacks into identical groups of mixed sheets stacked in proper sequence, as when gathering the individual pages of a book into the 30 complete pages of the book in sequence, comprising: a base frame, an endless conveyor means travelling in a pre-determined arcuate path in a closed arc on said base so as to be returned on each complete arc of travel cycle to its beginning point and having a plurality of individual 35 sheet stations accommodating sheet stacks travelling in a fixed position thereon, said sheet stacks being arranged in stacks of substantially vertically disposed sheets with individual stacks spaced in sequence of desired succession along the arc of said endless conveyor, a vacuum sheet transfer device movably mounted for operation adjacent each of said sheet stations, a vacuum line operatively connected with each of said respective vacuum devices, a track timing member mounted on said frame and extending coextensively with said endless means for at least a 40 portion of the arc thereof and having portions thereof out of alignment with other portions thereby causing said track to run in other than a single plane, a control support member on each of said transfer devices adapted to move said transfer device in response to movements 45 imparted thereto, said control support having a portion thereof contacting and following said track thereby being in response to the changes in direction thereof whereby said control support is moved by said change of track, a main vacuum line for all of said vacuum lines, a valve 50 control device having a valve timing cover mounted on said frame in communication with said main vacuum line and a timing plate mounted with said endless member in communicable vacuum relation with said cover when said endless means is moving, said timing plate receiving all of 55 the vacuum lines for said respective transfer devices and moving to receive selectively vacuum from said main line and to transfer said vacuum without loss selectively to one of said vacuum devices, said valve control device and said transfer members being timed and synchronized with each 60 other and said endless means to deliver suction to said respective vacuum devices when said cups engage a sheet to move same and to terminate suction when said sheet has reached delivery position of release, and means for accumulating said sequence of delivered sheets in a mixed 65 stack.

6. Apparatus for gathering signature sheets and the like from a plurality of individual stacks into identical groups of mixed sheets stacked in proper sequence, as when gathering the individual pages of a book into the 70 complete pages of the book in sequence, comprising a base

frame, an endless conveyor means travelling in a pre-determined arcuate path on said base so as to be returned on each complete cycle of movement to its beginning point and having a plurality of individual sheet stations accommodating sheet stacks travelling in a fixed position thereon, said stacks being arranged in proper sequence along said endless means, a sheet transfer device mounted for movement adjacent each of said endless means and adapted to engage sheets in succession on said endless means as said endless means moves continuously past a fixed point on said base, there being a sheet transfer member adjacent each of said sheet stations on said endless member, a substantially vertically movable lift support member on said transfer member, a vacuum suction member supported by each of said respective lift support members and being substantially vertically movable into engagement with the top sheet of the stack respectively adjacent thereto thereby engaging said sheet to lift same from its stack, a control support member on each of said respective transfer members, a control track mounted adjacent said endless means and extending in places substantially coextensively therewith, said control track having first position and other positions out of alignment therewith representing sheet engagement positions, said control support members in contact to travel along said track member and to change position in response to the positions thereon whereby said vacuum suction members are lowered to the respective top sheet by movement thereof, a vacuum line for each of said vacuum members, a main vacuum line for delivering suction to all of said vacuum lines, a valve control device having a valve timing cover inlet fixedly mounted on said frame and a timing plate mounted on said endless member in communicable vacuum relation with said cover when moving, said timing plate receiving all of the vacuum lines for said respective transfer devices and being adapted to selectively receive vacuum from said cover and distribute same to the proper transfer vacuum member, said vacuum valve control device and said transfer members being timed and synchronized with each other and said endless means to deliver suction to said respective vacuum suction members when said members engage a sheet to move same and to terminate suction when said sheet has reached delivery position of release, and an accumulating position on said machine.

7. Apparatus for gathering signature sheets and the like from a plurality of individual stacks into identical groups of mixed sheets stacked in proper sequence, as when gathering the individual pages of a book in to the complete pages of the book in sequence, comprising, an endless conveyor means travelling in a pre-determined arcuate path on said base so as to be returned on each complete cycle of movement to its beginning point and having a plurality of individual sheet stations accommodating sheet stacks travelling in a fixed position thereon, a sheet transfer device mounted for movement adjacent said endless means and adapted to engage sheets in succession on said endless member as said endless member moves continuously past a fixed point on said base, said transfer member being movable into engagement with said sheet and movable with said sheet from its stack, vacuum support member on said transfer device supporting a vacuum member for engagement with one of the sheets in any stack adjacent said transfer means to engage and temporarily hold said sheet, a control means on said base adapted to move said transfer member and said vacuum member into engagement with a sheet and to move said transfer means with said sheet from its stack, a main vacuum line, a valve means comprising a central valve inlet receiving said main vacuum line in closed communication therewith, a connecting chamber between and in closed communication with said central valve inlet and selectively timed in communication with at least one of said vacuum members at such time as vacuum is delivered to that particular vacuum sheet engaging member, there

being relative motion between said connecting chamber and said inlets for said vacuum lines for said vacuum members, whereby at least one of said vacuum lines is selected for suction according to the relative position of said chamber and said inlets, and whereby those vacuum members not receiving suction are not in communication with said central inlet, said valve means being synchronized with timing means and said transfer means so that suction is applied and maintained when said vacuum member engages said sheet and said transfer means moves the vacuum member and the sheet and so that suction is broken when said sheet is moved from its stack to the position of accumulation of mixed sheets, and a sheet group accumulating position on said base at which sheets are received in sequence and retained until a complete stack is made, said endless means moving continuously with said stacks thereon and said transfer member operating as said endless member moves to engage and move sheets in sequence.

8. Apparatus for gathering signature sheets and the like from a plurality of individual stacks into identical groups of mixed sheets stacked in proper sequence, as when gathering the individual pages of a book into the complete book, comprising, a base, an endless sheet conveyor means travelling in a pre-determined arcuate path on said base so as to be returned on each complete cycle of movement to its beginning point and having a plurality of individual sheet stations accommodating sheet stacks travelling in a fixed position with said endless means, a sheet transfer means movable adjacent each sheet station and stack for engaging said sheet stacks spaced in sequence thereon and moving sheets in sequence from its respective stack during continuous movement of said endless member, a vacuum sheet engaging member on each of said transfer means for engaging said sheets and for temporarily holding same until movement is complete as sheets are moved respectively in sequence, first control means associated with said endless means and said transfer means for controlling the movement thereof thereby controlling the transfer of sheets in sequence, a vacuum line for each of said vacuum members on said transfer means, a main vacuum line, a central vacuum control valve selectively operable to control the application of vacuum on said line and the loss of vacuum, comprising a central valve inlet receiving said main vacuum line in closed communication therewith, a closed connecting chamber between and in communication with said central valve inlet and selectively timed in communication with at least one of a plurality of the inlets for said vacuum lines for said vacuum members at such time as vacuum is delivered to that particular vacuum sheet engaging member, there being relative motion between said connecting chamber and said individual vacuum lines for said vacuum members, whereby at least one of said vacuum lines is selected for suction according to the relative position of said chamber and said inlets, and whereby those vacuum members not receiving suction are not in communication with said central inlet, said vacuum member holding sheets by means of the suction and releasing said sheets upon the termination of said vacuum, said control means and said vacuum valve being synchronized with each other and timed with said endless member so that vacuum is applied when sheets are engaged and moved and vacuum is terminated when sheets are positioned for release, and a sheet receiving and accumulating means for receiving said sheets in sequence into a mixed stack, said endless member transporting said stacks for removal of individual sheets thereon at said accumulating means and continuing in endless operation to effectuate removal of complete mixed groups upon each cycle of movement thereof.

9. Apparatus for gathering signature sheets and the like from a plurality of individual stacks into identical groups of mixed sheets stacked in proper sequence, as when gathering the individual pages of a book into the complete

pages of the book in sequence, comprising, a base frame, an endless conveyor means travelling in a pre-determined arcuate path on said base so as to be returned on each complete cycle of movement to its beginning point and having a plurality of individual sheet stations accommodating sheet stacks travelling in a fixed position thereon, said stacks being arranged in proper sequence along said endless means, a sheet transfer device mounted for movement adjacent each of said endless means and adapted to engage sheets in succession on said endless member as said endless member moves continuously past a fixed point on said base, there being a sheet transfer member adjacent each of said sheet stations on said endless means, a vacuum member supported by each of said transfer members, said transfer members being movable to bring said vacuum member into engagement with one of the sheets in the respective stack thereby and being movable with said sheet from said stack, a transfer control member mounted on each of said transfer members, a transfer control guide mounted on said frame and having positions thereon in pre-determined relation to said stations and engageable with each of said transfer control members as said transfer control members move with said endless member, certain of said guide positions representing sheet engaging positions and other positions representing sheet moving positions so that the position at which said transfer member engages said guide member controls the operation of said transfer means, a vacuum line for each of said vacuum members, a main vacuum line, a vacuum control valve between said main line and said other lines selectively delivering suction to said respective vacuum member at the proper time to engage said sheet and comprising a central valve inlet receiving said main vacuum line in closed communication therewith, a closed connecting chamber between and in communication with said central valve inlet and selectively timed in communication with at least one of a plurality of the inlets for said vacuum lines for said vacuum members at such time as vacuum is delivered to that particular vacuum sheet engaging member, there being relative motion between said connecting chamber and said individual vacuum lines for said vacuum members, whereby at least one of said vacuum lines is selected for suction according to the relative position of said chamber and said inlets, and whereby those vacuum members not receiving suction are not in communication with said central inlet, said vacuum control valve and said transfer control members being synchronized with each other and said endless means to deliver suction at the time the sheets are to be moved, and means for accumulating stacked sheets delivered thereto in sequence.

10. The device in claim 9 including means associated with said vacuum control valve for preventing the suction from being applied to a subsequent sheet where a previous sheet has failed to be picked up, by causing a loss in vacuum through said main vacuum line and through said connecting chamber and through the respective inlet to the vacuum member which did not pick-up thereby breaking the suction to the next valve inlet which is opened to said connecting chamber which has already been opened to the atmosphere through said vacuum member that did not make a closed seal with the sheet.

11. Apparatus for gathering signature sheets and the like from a plurality of individual stacks into identical groups of mixed sheets stacked in proper sequence, as when gathering the individual pages of a book into the complete pages of the book in sequence, comprising: a base frame, an endless conveyor means travelling in a pre-determined arcuate path in a closed arc on said base so as to be returned on each complete arc of travel cycle to its beginning point and having a plurality of individual sheet stations accommodating sheet stacks travelling in a fixed position thereon, said sheet stacks being arranged in stacks of substantially vertically disposed sheets with individual stacks spaced in sequence of desired succession

along the arc of said endless conveyor, a sheet transfer device mounted for operation adjacent each of said sheet stations and having a substantially vertical guide and support member, a cup support member mounted for substantial vertical movement on each of said respective vertical guide and support members, a vacuum cup mounted on each of said respective cup support members, a vacuum line operatively connected with each of said respective vacuum cups, said cup support being positioned with a portion thereof above said sheet stack and said vacuum cup thereon being positioned thereon for dropping into engagement with one of said sheets in said stack and with successive sheets thereon, a track timing member mounted on said frame and extending coextensively with said endless means for at least a portion of the arc thereof, and having portions thereof out of alignment with other portions thereby causing said track to run in other than a single plane, a control support member on each of said transfer devices adapted to move said cup support member in response to movements imparted thereto, said control support having a portion thereof contacting and following said track thereby being in response to the changes in direction thereof whereby said control support is moved by said change of track, a main vacuum line for all of said vacuum lines, a valve control device mounted on said frame in communication with said main vacuum line and adapted to receive selectively vacuum from said main line and to transfer said vacuum without loss selectively to one of said vacuum cups, and comprising a central valve inlet receiving said main vacuum line in closed communication therewith, a closed connecting chamber between and in communication with said central valve inlet and selectively timed in communication with at least one of a plurality of the vacuum lines for said vacuum cups at such time as vacuum is delivered to that particular vacuum sheet engaging cup, there being relative motion between said connecting chamber and said vacuum lines for said vacuum cups, whereby at least one of said vacuum lines is selected for suction according to the relative position of said chamber and said inlets, and whereby those vacuum members not receiving suction are not in communication with said central inlet, said vacuum control valve device and said transfer members being timed and synchronized with each other and said endless means to deliver suction to said respective vacuum cup when said cups engage a sheet to move same and to terminate suction when said sheet has reached delivery position of release, and means for accumulating said sequence of delivered sheets in a mixed stack.

12. Apparatus for gathering signature sheets and the like from a plurality of individual stacks into identical groups of mixed sheets stacked in proper sequence, as when gathering the individual pages of a book into the complete pages of the book in sequence, comprising: a base frame, an endless conveyor means travelling in a pre-determined arcuate path in a closed arc on said base so as to be returned on each complete arc of travel cycle to its beginning point and having a plurality of individual sheet stations accommodating sheet stacks travelling in a fixed position thereon, said sheet stacks being arranged in stacks of substantially vertically disposed sheets with individual stacks spaced in sequence of desired succession along the arc of said endless conveyor, a sheet transfer device mounted adjacent each of said sheet stations and having a substantially vertical guide and support member, a cup support member mounted for substantial vertical movement on each of said respective vertical guide and support members, a vacuum cup mounted on each of said respective cup support members, a vacuum line operatively connected with each of said respective vacuum cups, said cup support being positioned with a portion thereof above said sheet stack and said vacuum cup thereon being positioned thereon for dropping into engagement with one of said sheets in said stack and with

successive sheets thereon, a track timing member mounted on said frame and extending coextensively with said endless means for at least a portion of the arc thereof and having portions thereof out of alignment with other portions thereby causing said track to run in other than a single plane, a control support member on each of said transfer devices adapted to move said cup support member in response to movements imparted thereto, said control support having a portion thereof contacting and following said track thereby being in response to the changes in direction thereof whereby said control support is moved by said change of track, a main vacuum line for all of said vacuum lines, a valve control device having a valve timing cover mounted on said frame in communication with said main vacuum line and a timing plate mounted with said endless member in communicable vacuum relation with said cover when said endless means is moving, said timing plate receiving all of the vacuum lines for said respective transfer devices and moving to receive selectively vacuum from said main line and to transfer said vacuum without loss selectively to one of said vacuum cups, said valve control device and said transfer members being timed and synchronized with each other and said endless means to deliver suction to said respective vacuum cup when said cups engage a sheet to move same and to terminate suction when said sheet has reached delivery position of release, and means for accumulating said sequence of delivered sheets in a mixed stack.

13. In a timing device for distributing vacuum or pressure from a central line to a plurality of moving lines, a valve device having a valve cover, a main line in communication with an opening through said cover, said cover having said opening therein in position to distribute from said incoming line, a recessed chamber formed in said cover into which said opening leads, a vacuum timing plate mounted with said moving lines, a conduit connection on said plate with each of said lines to which vacuum or pressure is to be distributed, an opening in said timing plate for each of said conduit connections and said openings being exposed on said plate to communicate with said valve cover, said valve chamber having a planar surface, said timing plate having a planar surface juxtaposed in close association with the planar surface of said cover whereby said plate is movable about said cover, and means on said timing device for preventing operation of subsequent lines when there has been a failure to communicate properly on a preceding line.

14. In a timing device for distributing vacuum or pressure from a central line to a plurality of moving lines,

a valve device having a valve cover, a main line in communication with said cover, a means on said cover to transfer from said main line, a vacuum timing plate mounted with said moving lines, a conduit connection with each of said lines to which vacuum or pressure is to be distributed, an opening in said timing plate for each of said conduit connections and said openings being exposed on said plate to communicate with said valve cover, said valve cover having a planar surface, said timing plate having a planar surface juxtaposed in close association with the planar surface of said cover whereby said plate is movable about said cover to communicate therewith, means on said timing device causing loss in subsequent lines where there has been a loss in the preceding line thereby preventing further operation beyond initial failure.

15. In a timing device for distributing vacuum or pressure from a central line to a plurality of moving lines, a valve device having a valve cover, a main line in communication with an opening through said cover, said cover having said opening therein in position to distribute from said incoming line, a recessed chamber formed in said cover into which said opening leads, a vacuum timing plate mounted with said moving lines, a conduit connection on said plate with each of said lines to which vacuum or pressure is to be distributed, an opening in said timing plate for each of said conduit connections and said openings being exposed on said plate to communicate with said valve cover, said valve chamber having a planar surface, said timing plate having a planar surface juxtaposed in close association with the planar surface of said cover whereby said plate is movable about said cover, and said chamber in said cover being in communication with more than one of said conduit connections openings in said plate whereby loss of vacuum or pressure in one of said openings causes loss of vacuum or pressure in the other opening in communication with said chamber at that time thereby assuring a proper communication of said first openings prior to the operation of the opening thereafter.
